CLAIM

The ornamental design for connector coupling for a hearing aid, as shown and described.

DESCRIPTION

FIG. 1 is a top perspective view of a connector coupling for a hearing aid showing my new design;
FIG. 2 is a bottom perspective view thereof;
FIG. 3 is a top view thereof;
FIG. 4 is a side view thereof, all side views being identical; and,
FIG. 5 is a bottom view thereof.

FIG.1

FIG. 2

FIG. 3

FIG. 4

FIG. 5
